HIGHWAY MARKER

Charles T. Russ, Norwich, Conn.

Application January 11, 1943, Serial No. 472,037

3 Claims. (Cl. 88—79)

This invention relates to highway markers for reducing to a minimum hazardous conditions and especially adapted for indicating traffic lanes of a roadway.

The primary object of the invention is the provision of markers including light reflecting means and construction to permit the locating of the markers in a roadbed flush with the surface of said roadbed so as not to offer obstructions to traffic and be capable of reflecting light rays from a vehicle at angles to be seen by the occupants of said vehicle and thereby act as a guidance in the direction of travel to prevent accidents with other traffic.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

Figure 1 is a diagrammatical view showing a roadway wherein the traffic lanes thereof are formed through the use of markers constructed in accordance with my invention.

Figure 2 is a top plan view illustrating one of the markers positioned in a roadbed.

Figure 3 is a sectional view taken on the line 3—3 of Figure 2.

Referring in detail to the drawing, the numeral 5 indicates diagrammatically a roadway, wherein traffic lanes are indicated by markers 6 forming the subject matter of the present invention. In installing the markers, they are spaced a selected distance apart, so that traffic travelling in opposite directions will be guided to prevent the traffic of the lanes from encroaching on each other and resulting in collisions or other serious accidents.

Each marker 6 is embedded in the roadbed so that the top surface thereof is flush with the surface of the roadbed to permit the wheels of the vehicles to pass smoothly thereover and which reduces to a minimum the breakage of the markers by a vehicle contacting therewith and also eliminates obstructions over which pedestrians may trip.

Primarily the marker 6 consists of transparent panels 7 of glass or any other suitable material, an anchoring base 8 and reflectors 9. The base 8 may be of any suitable rigid material which is durable and is of triangular shape in cross section with the apex thereof disposed uppermost presenting converging walls 10 and a flat bottom

supporting wall 11. The reflectors 9 in the form of plates are secured on the walls 10 covering a portion of each wall 10 and extending downwardly from the apex of the base. The reflector may be cemented or otherwise secured on the base.

The transparent panels 7 are arranged to extend from the walls 10 of the base in opposite directions and each being of a width equal to the length of the base and of a thickness at the end 10 next to the base to cover the reflector lying between said end and the base.

The panel gradually decreases in thickness from said end to its free end by having the bottom wall thereof sloped while the top wall remains 15 straight to lie flush with the surface of the roadway. The panels may be cemented or otherwise secured to the reflectors and the latter being secured to the base permits the handling and installing of the device as a single unit construction.

20 The roadbed is recessed to accommodate the marker, as shown in Figure 3, whereby the marker becomes fixed against displacement by traffic engaging and passing thereover.

The light rays from a vehicle passing through 25 the panel next to the vehicle is reflected upwardly and toward the vehicle by the reflector next thereto, so as to render the marker readily viewable to the driver of said vehicle, consequently providing an efficient guide to said driver at night or in weather wherein the visibility is bad.

The construction of the device permits light reflection to be had to vehicles travelling in opposite directions to each other, so that the drivers of said vehicles will be guided to assure passing 35 without danger of collision.

If desired, when the indicators or markers are employed on a curve in a roadway, the panels 7 may be colored red or some other color that is readily distinguishable from markers located in a straight portion of the roadway. This will notify a driver of a curve in the roadway in sufficient time to permit the driver to have complete control over the vehicle on entering the curve, consequently resulting in safer driving.

45 While I have shown and described the preferred embodiment of my invention, it will be understood that minor changes in construction, combination and arrangement of parts may be made without departing from the spirit and scope of the invention as claimed.

Having thus described my invention, what I claim is:

1. In a highway marker, elongated transparent panels sunk in a bed of a roadway and provided with top flat surfaces flush with the surface of

the roadway, an anchoring base arranged between said panels and having converging walls disposed opposite to the panels, and reflectors supported by the walls and protected by the panels.

2. In a highway marker, a pair of elongated transparent panels arranged in endwise relation and spaced from each other and sunk in a roadbed and provided with flat top surfaces lying flush with the surface of the roadway, a triangular shaped base arranged between the adjacent ends of the panels and having sloping walls opposing the adjacent ends of the panels, reflectors mounted on said walls and contacted by the adjacent ends of the panels for protection thereby. 15

3. In a highway marker, a pair of elongated transparent panels arranged in endwise relation and spaced from each other and sunk in a roadbed and provided with flat top surfaces lying flush with the surface of the roadway, a triangular shaped base arranged between the adjacent ends of the panels and having sloping walls opposing the adjacent ends of the panels, reflectors mounted on said walls and contacted by the adjacent ends of the panels for protection thereby, and means for securing the panels, reflectors and base together.

CHARLES T. RUSS.
